UNITED STATES PATENT OFFICE.

JOSEPH D. WESTGATE, OF MANCHESTER, NEW HAMPSHIRE.

BED-LOUNGE.

SPECIFICATION forming part of Letters Patent No. 252,283, dated January 10, 1882.

Application filed November 7, 1881. (No model.)

To all whom it may concern:

Be it known that I, JOSEPH D. WESTGATE, of Manchester, in the county of Hillsborough and State of New Hampshire, have invented 5 an Improvement in Bed-Lounges, of which the following description, in connection with the accompanying drawings, is a specification.

In this my invention I have provided the usual lounge-frame with an auxiliary drawer-like reversible frame having trunnions located, as hereinafter described, at its ends, the said trunnions being fitted to notches or bearings in horizontally-sliding bars properly held and guided in the main lounge-frame, the said bars 10 supporting the auxiliary frame and permitting it to be drawn out in front of the lounge when it is desired to convert the lounge into a bed, the said auxiliary frame at such time being reversed or turned over on its trunnions, bringing what was its under side up into a higher level in line with the top of the main part of the lounge, when suitable folding legs carried by the auxiliary frame, the said legs having proper fastening devices, will be turned down 15 and rest upon the floor. The main head-piece of the lounge has fitted under it an auxiliary head-piece, which is pivoted upon a curved arm or lever so shaped that when the auxiliary head is turned or swung out from under it, it will 20 be placed end to end with the main head-piece. The front board of the lounge is held at each end by pivoted links, thus adapting it to be thrown down when it is desired to withdraw the auxiliary frame from under the main frame. 25

Figure 1 represents in front elevation the frame of a lounge embodying my invention, the front board being elevated with the auxiliary frame inclosed within the main frame. Fig. 2 shows a like view of the lounge, but with the 30 front board lowered and the auxiliary frame drawn out, reversed, and supported by its legs. Fig. 3 is a vertical cross-section of Fig. 1, in the dotted line $x-x$; Fig. 4, a similar section of Fig. 2, in the line $x'-x'$; and Fig. 5 is a detail to be referred to, showing the main head-piece and the auxiliary head-piece and its carrying-arm.

The lounge is not shown as upholstered, but it may be in any usual way.

50 The frame a of the lounge-back a^2 , head a^3 , and legs a^4 are substantially as usual.

The end pieces, b , of the main frame of the lounge have attached to or made in them suitable guideways, b^2 , either by the addition of metal strips m or otherwise, (see Fig. 4,) to receive the slide-bars b^3 , of suitable size and strength, the said slide-bars having at their outer ends suitable notches or bearings to receive the projecting journals c of the metal plates c' , which are secured externally to the 60 end pieces of the auxiliary frame and project therefrom in the direction of the length of the said auxiliary frame, as shown in Figs. 2 and 3.

The journals c are located nearest the under side of the auxiliary frame d , when the latter 65 is in position in the main frame a , as in Fig. 3, so that when the auxiliary frame is drawn out and inverted, its journals turning in their bearings, the under side of the frame will be brought into a plane higher than that occupied by the 70 upper side of the frame in the position Fig. 3, thus elevating the under side of the frame d in a very simple manner up to the level of the top of the main frame.

The auxiliary frame has two of its corner legs, 75 d' , pivoted upon pins d^2 . These legs are thus adapted to fold within the frame, as in Fig. 3, or be turned out, as in Fig. 4. These legs have suitable fastening devices to hold them in their desired positions, such fastening devices 80 being shown as a pin, d^3 , extended through the upper end of the leg and pressed upon by a spring, 2, the pin d^3 being permitted to move longitudinally through the leg and engage the side bars to hold the leg in either of its positions. 85

The front board, e , of the main frame of the lounge is connected by pivots at each end with links e' , in turn pivoted at e^2 upon a rigid part of the main frame, so that the said front board 90 may be raised and lowered and be held elevated, as in Figs. 1 and 3, or lowered, as in Figs. 2 and 4, it occupying the latter position when the auxiliary frame d is to be withdrawn. Assuming that the front board has been lowered, as shown in Figs. 2 and 4, the auxiliary 95 frame (see Fig. 3) may then be drawn out, as in Figs. 2 and 4, the slide-bars b^3 moving in the guideways and supporting the trunnions c' during such operation. As soon as the auxiliary 100 frame has been completely withdrawn it is reversed on its journals, bringing what was its

under side in Fig. 3 uppermost in Fig. 4, thus placing the said auxiliary frame at a higher level than that occupied by it when shoved into the main frame, as in Fig. 3. The auxiliary frame having been reversed, the legs d' are moved from their horizontal position, Fig. 3, to occupy their vertical position, Fig. 4, and support the outer corners of the auxiliary frame. Placing the journals c' nearest the lower or under side of the auxiliary frame (assuming it shut into the main frame, as in Fig. 3) enables the auxiliary frame, when reversed, as in Fig. 4, to be brought up into a higher level, and it is in this peculiarity that my invention chiefly consists. When reversed, as in Fig. 4, the auxiliary frame may be held in position or locked or clamped firmly to the main frame by any suitable clamping or locking devices.

Underneath the main head-piece a^3 , which in Fig. 1 is partially shown in section, I have arranged an auxiliary head-piece, f , and have pivoted the same near one end upon a curved arm, f^2 , shaped as shown in Fig. 5, with its end pivoted upon the main frame at 4 . When the auxiliary frame is drawn out, as in Fig. 4, this auxiliary head will be drawn back from under the main head, and the arm f^2 will be turned about horizontally, bringing the auxiliary head in line with the main head just above the end of the auxiliary frame, thus forming a head-piece for it, the said head-piece being in continuation of the main head-piece. This arm f^2 , it will be noticed, is so shaped or bent as to extend about the side supports of the main head-piece.

I claim—

1. In a bed-lounge, the main frame and the auxiliary frame, having journals c mounted upon slide-bars, as described, the auxiliary frame being adapted to be inverted, substantially as set forth, to bring it into a higher plane to coincide with the position occupied by the main frame.

2. The main framing and its slide-bars b^3 , combined with the auxiliary sliding and reversible frame d , and with pivoted legs d' , to operate substantially as described.

3. The main framing a , combined with the front board and its supporting-links e' , to operate substantially as described.

4. The main framing and main head-piece, combined with the auxiliary head-piece and its carrying-arm f^2 , shaped to permit the auxiliary head-piece to be placed under the main head-piece, or end to end with it as a continuation thereof, substantially as described.

5. The main frame-work and its head-piece and sliding bars b^3 , combined with the sliding reversible auxiliary frame d , having trunnions supported in bearings in the said slide-bars, and with the auxiliary head-piece and its pivoted carrying-arm f^2 , to operate substantially as described.

In testimony wherof I have signed my name to this specification in the presence of two subscribing witnesses.

JOSEPH D. WESTGATE.
